UNITED STATES PATENT OFFICE

131,705

DESIGN FOR A SINGLE CYLINDER ENGINE

Henry Schreck, Beloit, Wis., assignor to Fairbanks, Morse & Co., Chicago, Ill., a corporation of Illinois

Application July 29, 1940, Serial No. 93,996

Term of patent 14 years

To all whom it may concern:

Be it known that I, Henry Schreck, a citizen of the United States, residing in the city of Beloit, county of Rock, State of Wisconsin, have invented a new, original, and ornamental Design for a Single Cylinder Engine, of which the following is a specification, reference being had to the accompanying drawings, forming a part thereof.

In the drawings: Fig. 1 is an elevational view of the engine as it appears from the rear or fly wheel end thereof; Fig. 2 is a side elevation as

viewed from the right side of the engine of Fig. 1; Fig. 3 is a front or forward end elevational view of the engine; Fig. 4 is a side elevational view as seen from the left side of the engine appearing in Fig. 1, and Fig. 5 is a top plan view of the engine.

I claim:

The ornamental design for a single cylinder engine, substantially as shown.

HENRY SCHRECK.
